CAKE OF SOAP

Leslie Weiss, Bronx, N.Y., assignor to Schwartz Engraving & Die Works, Inc., New York, N.Y., a corporation of New York

Filed Apr. 4, 1961, Ser. No. 64,607

Term of patent 14 years

(Cl. D73—1)

FIG. 1

FIG. 2

FIG. 3

FIG. 4

FIG. 1 is a top view of a cake of soap embodying my new design;

FIG. 2 is a bottom view thereof;

FIG. 3 is a side view; and

FIG. 4 is an end view thereof.

The side and end opposite to those of FIGS. 3 and 4 present a similar appearance.

The essential features of my design reside in the portions shown in solid lines on the drawing.

This application is a continuation-in-part of my application, Serial No. D. 58,617 filed December 9, 1959 and now abandoned.

I claim:

The ornamental design for a cake of soap, as shown and described.
